United States Patent Office

Des. 228,544

Patented Oct. 9, 1973

228,544

LIPSTICK CONTAINER

Roy S. Swenson, Danbury, Conn., assignor to The Risdon Manufacturing Company, Naugatuck, Conn.

Filed Nov. 8, 1971, Ser. No. 196,872

Term of patent 14 years

Int. Cl. D28—02

U.S. Cl. D86—10 G

FIG. 2

FIG. 1

FIG. 5

FIG. 3

FIG. 4

FIG. 1 is an exploded perspective view of a lipstick container showing my new design;

FIG. 2 is a top plan view;

FIG. 3 is a side elevational view;

FIG. 4 is a bottom plan view; and

FIG. 5 is a perspective view with enclosure in alternate position.

I claim:

The ornamental design for a lipstick container, substantially as shown.
